Primary Examiner — David N Brandt*(74) Attorney, Agent, or Firm* — Michael Dowler; Park, Vaughan, Fleming & Dowler LLP(57) **ABSTRACT**

Described herein are embodiments of systems and apparatuses that include a dart and/or a clutch for a dart plunger. In an exemplary embodiment, the clutch consists of a one-piece unit having a length, an outside diameter, and an inside diameter where at least a portion of the inside diameter is sized to create a frictional interface with a dart. The clutch may also include a gap, a slot, and/or a spiral cut. The dart may include a shaft having opposite ends and a shaft diameter that varies between the opposite ends.

DART AND CLUTCH ASSEMBLY

PRIORITY CLAIM

This application claims priority to provisional patent application Ser. No. 63/225,237 filed Aug. 3, 2021, and further to provisional patent application Ser. No. 63/278,423 filed Nov. 19, 2021, and further to provisional patent application Ser. No. 63/309,364 filed Feb. 17, 2022, each of which is fully incorporated herein by reference.

TECHNICAL FIELD OF THE INVENTION

Embodiments of the subject matter disclosed herein relate to an improved dart and clutch and assembly, and methods of operating and using the same.

DISCUSSION OF THE BACKGROUND

It is well known that production from oil and gas wells can suffer due to the build-up of fluids at the bottom of the well. Various methods and devices have been developed to remove those fluids so as to improve the well's productivity. The present invention assists in that process.

SUMMARY

The following presents a simplified summary of the invention in order to provide a basic understanding of some aspects of the invention. This summary is not an exhaustive overview of the invention. It is not intended to identify key or critical elements of the invention or to delineate the scope of the invention. Its sole purpose is to present some concepts in a simplified form as a prelude to the more detailed description that is later discussed.

Described herein are embodiments of systems and apparatuses that include a dart plunger wherein movement of the dart is at least partially controlled by a clutch. In an embodiment, of which there are others, including still others that will be appreciated by those skilled in the art having read the present specification and drawings, the dart has a shaft whose diameter varies from end to end, namely the shaft has a smaller diameter toward its opposite ends and a larger diameter between its opposite ends, and the clutch includes a one-piece device as described in more detail below in the detailed description of the invention.

BRIEF DESCRIPTION OF THE DRAWINGS

The disclosure may be understood by reference to the following description taken in conjunction with the accompanying drawings, in which like reference numerals identify like elements, and in which:

FIG. 1 is an assembly view of one embodiment of a prior art dart plunger;

FIG. 2 is a cross-sectional view of an assembled view of FIG. 1;

FIG. 3 is a partial assembly view of the dart plunger assembly shown in FIG. 1;

FIG. 4A is a side view of the dart and clutch assembly shown in FIG. 1;

FIG. 4B is a perspective view of the dart and clutch assembly shown in FIG. 1;

FIG. 5A is a side view of the clutch assembly shown in FIG. 1;

FIG. 5B is a front view of the clutch assembly shown in FIG. 1;

FIG. 5C is a perspective view of the clutch assembly shown in FIG. 1;

FIG. 6 is a perspective view of one embodiment of a dart plunger assembly including an exemplary embodiment of the present invention;

FIG. 7 is a partial cross-section view of the dart plunger assembly shown in FIG. 6;

FIG. 8A is a side view of an exemplary embodiment of a clutch assembly of the present invention;

FIG. 8B is a cross-section view taken along cross-sectional line A-A shown in FIG. 8A;

FIG. 9A is a top view of an exemplary embodiment of a clutch assembly of the present invention;

FIG. 9B is a side view of an exemplary embodiment of a clutch assembly of the present invention;

FIG. 9C is a bottom view of an exemplary embodiment of a clutch assembly of the present invention;

FIG. 9D is a perspective view of an exemplary embodiment of a clutch assembly of the present invention;

FIG. 10 is a cross-sectional view of an exemplary embodiment of a dart plunger assembly including an embodiment of the present invention;

FIG. 11 is an assembly view of an exemplary embodiment of a dart plunger assembly including an embodiment of the present invention;

FIG. 12 is a partial assembly view of an exemplary embodiment of a dart plunger assembly including an embodiment of the present invention;

FIG. 13 is a partial cross-section view of the dart plunger assembly shown in FIG. 11;

FIG. 14A is a top view of an exemplary embodiment of a clutch assembly of the present invention;

FIG. 14B is a side view of an exemplary embodiment of a clutch assembly of the present invention;

FIG. 14C is a perspective view of an exemplary embodiment of a clutch assembly of the present invention;

FIG. 15 is a perspective view of an exemplary embodiment of a clutch assembly of the present invention;

FIG. 17 is a front view of the embodiment of FIG. 15, including cross section line A-A;

FIG. 18 is a cross-sectional view of FIG. 17 taken along cross section line A-A in FIG. 17;

FIG. 19 is a perspective view of an exemplary embodiment of a dart of the present invention;

FIG. 20 is a perspective view of an exemplary embodiment of a dart of the present invention;

FIG. 21 is a top view of an exemplary embodiment of a dart of the present invention;

FIG. 22 is a side view of an exemplary embodiment of a dart of the present invention;

FIG. 23 is a bottom view of an exemplary embodiment of a dart of the present invention.

55 DETAILED DESCRIPTION

Various features and advantageous details are explained more fully with reference to the non-limiting embodiments that are illustrated in the accompanying drawings and detailed in the following description. Descriptions of well-known starting materials, processing techniques, components, and equipment are omitted so as not to unnecessarily obscure the invention. It should be understood, however, that the detailed description and the specific examples, while indicating embodiments of the invention, are given by way of illustration only, and not by way of limitation. Various substitutions, modifications, additions, and/or rearrange-

ments within the spirit and/or scope of the underlying inventive concept will become apparent to those skilled in the art from this disclosure.

The words and phrases used herein should be understood and interpreted to have a meaning consistent with the understanding of those words and phrases by those skilled in the relevant art. No special definition of a term or phrase, i.e., a definition that is different from the ordinary and customary meaning as understood by those skilled in the art, is intended or implied. To the extent that a term or phrase is intended to have a special meaning, i.e., a meaning other than that understood by skilled artisans, such a special definition will be expressly set forth in the specification in a definitional manner that directly and unequivocally provides the special definition for the term or phrase.

The present embodiments describe an improved dart and clutch assembly. FIG. 1 is an assembly view of one embodiment of a prior art dart plunger. Those skilled in the art will appreciate the purpose, function, and operation of a dart plunger.

Essentially, a dart plunger is a device for removing fluids from a well. The plunger is released into the top of a well, were it then travels/falls down the well. When it strikes the bottom (or a stopper) of the well, the plunger's dart is forced into its "closed" position, such that fluid and gases are substantially prohibited from passing through the interior of the plunger. When the pressure below the plunger is sufficiently greater than the pressure above the plunger, the plunger begins to rise (or travel up) toward the top of the well. This upward travel, in combination with the fact that gases and fluids cannot travel through the interior of the plunger, causes the plunger to push such liquids toward the top of the well, where they are eventually removed from the well.

When the plunger reaches the top of the well, a rod typically in the wellhead's lubricator forces the plunger's dart back into its "open" position, where liquids and gases are allowed to flow through the interior of the plunger. (The plunger includes a clutch that tends to keep the dart in its open or closed position, as the case may be) This causes the plunger to once again fall down the well, where the process/cycle is repeated. In this fashion, liquids can be removed from the well, thereby enabling the well to flow more freely, to the economic benefit of its producer.

As indicated, FIG. 1 is an assembly view of one embodiment of a prior art dart plunger. As shown, it includes a plunger body or mandrel 10, a dart or stem 20, a cage 30, a clutch 40 (in this case formed from two halves), a tensioning member 50 (such as garter springs, o-rings, or some other spring/elastomer), and an end nut 60. These are conventional components, as a person skilled in the art will appreciate. As can be seen and as those skilled in the art already will appreciate, dart 20 will substantially block flow through plunger body 10 when it is in its "closed" position, and will it will allow flow through plunger body 10 when it is in its "open" position. Clutch halves 40 (in combination with tensioning member(s) 50) keep dart 20 from freely moving between its open and closed position. Specifically, clutch halves 40 tend to keep dart 20 in either its open or closed position unless a push rod in the wellhead's lubricator (or some other device) forces dart 20 from its closed to its open position, or the plunger (with the dart extending through the bottom of the plunger in its open position) strikes the bottom of the well (or some other stopper device), thereby forcing dart 20 from its open to its closed position. End nut 60 keeps dart 20 and clutch 40 inside cage 30.

FIG. 2 is a cross-sectional view of an assembled view of FIG. 1. In particular, FIG. 2 shows the dart plunger in its open position, such that fluids and gases from the well can travel through opening(s) 31 in cage 30 and then up through the hollow interior of plunger body 10, as shown by the dashed arrows in FIG. 2. FIG. 2 also more clearly depicts the operation of clutch 40 on dart 20, whereby clutch 40 exerts a frictional force on dart 20 so as to generally maintain dart 20 in either its open (as shown in FIG. 2) or its closed position.

FIG. 3 is a partial assembly view of the dart plunger assembly shown in FIG. 1, more specifically showing the relationship between dart 20, clutch 40, tensioning members 50, and end nut 60. Specifically, in this particular embodiment, clutch 40 includes two halves, which are positioned around the stem of dart 20 so as to create the frictional force explained above to help maintain dart 20 in a stationary position. Notably, prior art clutches 40 consist of more than one piece, typically two, but also can include more than two pieces. Likewise, tensioning member 50 can consist of one or more separate members, the elasticity of which can be selected to assist in adjusting the friction between clutch 40 and dart 20. End nut 60 includes an interior passage sized to allow a portion of the stem of dart 20 to extend therethrough, thereby providing a surface against which dart 20 can strike the bottom of the well and force dart 20 from its open position to its closed position against the frictional force otherwise exerted by clutch 40 on dart 20.

FIG. 4A is a side view of the dart and clutch assembly shown in FIG. 1, and FIG. 4B is a perspective view of the dart and clutch assembly shown in FIG. 1. As explained above, the arrangement of dart 20 and clutch 40 enables dart 20 to slide between its open and closed position so long as the force causing the sliding operation is greater than the frictional force exerted on dart 20 by clutch 40. Such frictional force can be adjusted by a variety of means known to those skilled in the art, including adjusting the size and fit of clutch 40.

FIG. 5A is a side view of the clutch assembly 40 shown in FIG. 1. FIG. 5B is a front view of the clutch assembly 40 shown in FIG. 1. FIG. 5C is a perspective view of the clutch assembly 40 shown in FIG. 1. This particular clutch assembly functions as two halves as described above to exert a frictional force on dart 20 so as to prevent dart 20 from freely moving between its open and closed positions within the dart plunger of FIG. 1.

FIG. 6 is a perspective view of one embodiment of a dart plunger assembly including an exemplary embodiment of the present invention. Specifically, as shown, FIG. 6 depicts dart plunger 70, which includes plunger body 80, cage 90, dart 100, and end nut 110. As will be described in more detail below, dart plunger 70 includes at least an entirely new and different clutch mechanism (including various embodiments) over that of the dart plunger depicted in FIG. 1-5.

FIG. 7 is a partial cross-section view of the new dart plunger assembly shown in FIG. 6. As shown, FIG. 7 illustrates the relationship between cage 90, dart 100, end nut 110, and clutch 120. Notably, end nut 110 is depicted as a unibut in that it now houses, or retains, clutch 120. Moreover, while clutch 120 is entirely different from the prior art clutches, the general operation of the cage 90, dart 100, clutch 120 and end nut 110 operate similar to a prior art dart plunger in the sense that dart 100 has an open and closed position within the dart plunger.

FIG. 8A is a side view of one embodiment of clutch 120 shown in FIG. 7. As shown, this embodiment of clutch 120 is a single element (i.e., it is not a multi-piece clutch like

clutch 40) having a specific shape, sometimes referred to as a collet clutch. Namely, in this embodiment it is generally circular with at least one inside diameter sized to create a frictional interface with dart 100 and at least one outside diameter sized to seat snugly in end nut 110. Still further, this embodiment of clutch 120 includes at least one or more slots 121 so that the entire inner circumference of clutch 120 is not imparting a frictional force on dart 100. Likewise, this embodiment of clutch 120 includes one or more tapered sides so, once again, the entire inner circumference of clutch 120 is not imparting a frictional force on dart 100. Both slots 121 and the tapering of the sides of clutch 120 function at least in part so that clutch 120 does not wear out as fast as it otherwise would without the slots and/or tapered sides.

FIG. 8B is a cross-section view taken along cross-sectional line A-A shown in FIG. 8A. FIG. 8B better depicts the varying inside and outside diameters of that embodiment of clutch 120 as well as slots 121.

FIG. 9A is a top view of the embodiment of clutch 120 shown in FIGS. 8A and 8B. FIG. 9B is a side view of the embodiment of clutch 120 shown in FIGS. 8A and 8B. FIG. 9C is a bottom view of the embodiment of clutch 120 shown in FIGS. 8A and 8B. FIG. 9D is a perspective view of the embodiment of clutch 120 shown in FIGS. 8A and 8B. Like FIG. 8B, FIGS. 9A-9D better depict the varying inside and outside diameters of that embodiment of clutch 120 as well as slots 121.

FIG. 10 is a cross sectional view of another embodiment of a dart plunger assembly including another exemplary embodiment of the present invention. Specifically, as shown, FIG. 10 depicts dart plunger 70, which includes plunger body 80, cage 90, dart 100, and end nut 110. As will be described in more detail below, dart plunger 70 includes at least an entirely new and different clutch mechanism 130 (including various embodiments) over that of the dart plunger depicted in FIG. 1-5.

FIG. 11 is an assembly view of one embodiment of dart plunger 70 shown in FIG. 10. Specifically, FIG. 11 shows plunger body 80 coupled to cage 90. Further shown is the orientation in which dart 100 is inserted into cage 90, with clutch 130 to be mounted on dart 100, all of which is maintained in the body/cage combination by the threaded connection on end nut 110. See also FIG. 12, which illustrates the same detail. Note that this embodiment shows end nut 110 having a partial cutout in its sidewall. The purpose of this cutout is so that clutch 130 can be inserted into end nut 110 through the cutout. This same feature is shown in FIG. 7.

FIG. 13 is a partial cross-section view of the dart plunger assembly shown in FIG. 10. As shown, FIG. 13 illustrates the relationship between cage 90, dart 100, end nut 110, and clutch 130. While clutch 130 is entirely different from the prior art clutches, the general operation of the cage 90, dart 100, clutch 130 and end nut 110 operate similar to a prior art dart plunger in the sense that dart 100 has an open and closed position within the dart plunger.

FIG. 14A is a top view of the embodiment of clutch 130 shown in FIGS. 10-13. FIG. 14B is a side view of the embodiment of clutch 130 shown in FIGS. 10-13. FIG. 14C is a perspective view of the embodiment of clutch 130 shown in FIGS. 10-13.

As shown in FIGS. 14A-14C, this embodiment of clutch 130 has a particular shape and characteristics. Namely, this embodiment of clutch 130 includes a slit or gap 131, which as shown extends from the outside diameter to the inside diameter of clutch 130 along its entire length. One purpose of this gap is to give it some flexibility so, for example, the

clutch can be spread open to fit onto the outside diameter of the dart. Moreover, this embodiment of clutch 130 includes outer surface/diameter 133 that in this embodiment is uniform and sized to snugly fit within end nut 110 and/or cage 90. This embodiment of clutch 130 also includes undulating inside surface/diameter 132. In other embodiments, the inside surface/diameter 132 is not undulating. The purpose of undulating inside surface/diameter 132 is at least so the entire inside surface/diameter of clutch 130 does not contact dart 100. Finally, as best illustrated by FIG. 14A, the center point (or origin) of the outside diameter of clutch 130 is not the same as the center point (or origin) of the inside diameter of clutch 130. As shown, the sidewall of clutch 130 opposite gap 131 is thicker than the sidewall of clutch 130 at gap 131. Accordingly, the thicker sidewall opposite gap 131 is less inclined to crack or break since it is thicker in that region than in other regions of clutch 130, which is believed to be an advantage since the side of clutch 130 opposite gap 131 receives more stress than other regions of clutch 130 due to its location opposite gap 131. That said, other embodiments of clutch 130 include inside and outside diameters on the same center.

FIG. 15 is a perspective view of yet another embodiment of a clutch 140 for use in a dart plunger. As shown, this particular embodiment of clutch 140 has an undulating inside diameter 141 akin to that of clutch 130 shown in FIGS. 10-14 in that it includes at least one inside diameter sized to create a frictional interface with dart 100. Unlike the embodiment of clutch 130, however, this embodiment of clutch 140 includes an outside diameter 142 (than can be smooth or not, i.e., ribbed) that is further characterized by spiral cut 143, which in this embodiment begins on the top surface of clutch 140 and ends on the bottom surface of clutch 140. The outside diameter of clutch 140 is sized to seat snugly in either end nut 110 or within cage 90. Other embodiments of clutch 140 are contemplated as specifically within the scope of the present invention. For example, spiral cut 143 need not extend from the top to the bottom of clutch 140. Likewise, the inside diameter of clutch 140 need not include undulating surface 141.

FIG. 16 is a top view of the embodiment of FIG. 15. Once again, this particular embodiment of clutch 140 is shown including undulating inside diameter 141, outside diameter 142, and the beginning (on the top surface) of spiral cut 143. Likewise, FIG. 17 is a front view of the embodiment of FIG. 15, including cross section line A-A. Once again, outside diameter 142 and spiral cut 143 are visible. FIG. 18 is a cross-sectional view of FIG. 17 taken along cross section line A-A in FIG. 17 to once again illustrate undulating inside diameter 141, outside diameter 142, and spiral cut 143.

FIG. 19 is a perspective view of one exemplary embodiment of dart 100 of the present invention. While other embodiments of dart 100 previously depicted as part of the present invention show dart 100 as having a shaft of substantially constant diameter (see FIGS. 6, 7, 10, 11, 12, and 13), FIGS. 19-23 illustrate yet another embodiment of the dart of the present invention. Specifically, FIG. 19 illustrates dart 150 as having a shaft whose diameter varies from terminal end 150a to terminal end 150c, namely in this embodiment the shaft has a smaller diameter toward its opposite terminal ends and a larger diameter between its opposite terminal ends, such as at midpoint 150b. (Note that as shown in FIGS. 19-23, the term "opposite ends" does not necessarily mean the absolute ends of the dart, but "opposite terminal ends" does.) The idea is that the shaft experiences more friction with its corresponding clutch toward the middle of the shaft than it does at other portions of the shaft,

such as toward the opposite ends of the shaft. This reduces tension and/or wear on the clutch when compared to a shaft of constant diameter since the dart only transitions between its open and closed positions a fraction of the time that it is in use.

FIG. 20 is another perspective view of this particular embodiment of dart 150. FIG. 21 is a top view of the same embodiment. FIG. 22 is a side view, and FIG. 23 is a bottom view of the same embodiment. Put differently, each embodiment of FIGS. 19-23 include a dart shaft having a central region 150b of increased diameter relative to other regions of the dart's shaft.

Although the invention(s) is/are described herein with reference to specific embodiments, various modifications and changes can be made without departing from the scope of the present invention(s), as set forth in the claims below. Accordingly, the specification and Figures are to be regarded in an illustrative rather than a restrictive sense, and all such modifications are intended to be included within the scope of the present invention(s). Any benefits, advantages, or solutions to problems that are described herein with regard to specific embodiments are not intended to be construed as a critical, required, or essential feature or element of any or all the claims.

Unless stated otherwise, terms such as "first" and "second" are used to arbitrarily distinguish between the elements such terms describe. Thus, these terms are not necessarily intended to indicate temporal or other prioritization of such elements. The terms "coupled" or "operably coupled" are defined as connected, although not necessarily directly, and not necessarily mechanically. The terms "a" and "an" are defined as one or more unless stated otherwise. The terms "comprise" (and any form of comprise, such as "comprises" and "comprising"), "have" (and any form of have, such as "has" and "having"), "include" (and any form of include, such as "includes" and "including") and "contain" (and any form of contain, such as "contains" and "containing") are open-ended linking verbs. As a result, a system, device, or apparatus that "comprises," "has," "includes" or "contains" one or more elements possesses those one or more elements but is not limited to possessing only those one or more elements. Similarly, a method or process that "comprises," "has," "includes" or "contains" one or more operations possesses those one or more operations but is not limited to possessing only those one or more operations.

Accordingly, the protection sought herein is as set forth in the claims below.

The invention claimed is:

1. A dart plunger, comprising:
a dart having a first position in the dart plunger and a second position in the dart plunger, wherein the dart is configured in the dart plunger to move between the first and the second position;
the dart including a shaft having a first terminal end, a second terminal end, a midpoint equidistant between the first terminal end and the second terminal end, a region of increased diameter at the midpoint, a first region of decreased diameter between the first terminal end and the midpoint, and a second region of decreased diameter between the second terminal end and the midpoint;
a clutch for retarding movement of the dart between the first and the second position, wherein the clutch is a one-piece unit having a length, an outside diameter, and an inside diameter, wherein the inside diameter is sized to create a frictional interface with the shaft's region of increased diameter and each of the first region of decreased diameter and the second region of decreased diameter; and
wherein the clutch includes a spiral cut in at least a portion of the outside diameter of the clutch.
2. The dart plunger of claim 1 wherein the spiral cut in the outside diameter of the clutch begins on a top surface of the clutch and ends on a bottom surface of the clutch.
3. The dart plunger of claim 2 wherein the inside diameter of the clutch further includes an undulating inside diameter so that the entire inside diameter of the clutch does not create the frictional interface with the dart.
4. The dart plunger of claim 3 wherein the first position of the dart is an open position such that fluids from a well can flow through the dart plunger.
5. The dart plunger of claim 3 wherein the second position of the dart is a closed position such that fluids from a well do not flow through the dart plunger.
6. The dart plunger of claim 1 wherein the spiral cut extends from the outside diameter to the inside diameter of the clutch.
7. The dart plunger of claim 6 wherein the clutch further includes a bore having a spiral cut surface in contact with the dart's shaft as the dart moves between the first and second position.
8. The dart plunger of claim 7 wherein the spiral cut surface in the clutch's bore extends from a top surface to a bottom surface of the clutch.
9. The dart plunger of claim 8 wherein the spiral cut surface in the clutch's bore extends continuously from the top surface to the bottom surface of the clutch.
10. The dart plunger of claim 9 wherein the clutch may be positioned on the shaft's first region of decreased diameter, the shaft's second region of decreased diameter, or the shaft's region of increased diameter.
11. The dart plunger of claim 10 wherein the clutch is oriented in the dart plunger to repeatedly transition between being positioned on either of the shaft's first region of decreased diameter, the shaft's second region of decreased diameter, and the shaft's region of increased diameter.
12. The dart plunger of claim 5 wherein the clutch may be positioned on the shaft's first region of decreased diameter, the shaft's second region of decreased diameter, or the shaft's region of increased diameter.
13. The dart plunger of claim 12 wherein the clutch is oriented in the dart plunger to repeatedly transition between being positioned on either of the shaft's first region of decreased diameter, the shaft's second region of decreased diameter, and the shaft's region of increased diameter.
14. The dart plunger of claim 1 including an end nut, wherein the clutch seats in the end nut.
15. The dart plunger of claim 14 wherein the end nut includes sidewalls.
16. The dart plunger of claim 15 wherein the sidewalls include a cutout.
17. The dart plunger of claim 16 wherein the cutout is sized to receive the clutch therethrough.
18. A dart plunger, comprising:
a dart having a first position in the dart plunger and a second position in the dart plunger, wherein the dart is configured in the dart plunger to move between the first and the second position;
the dart including a shaft having a first terminal end, a second terminal end, a midpoint equidistant between the first terminal end and the second terminal end, a region of increased diameter at the midpoint, a first region of decreased diameter between the first terminal end and the midpoint, and a second region of decreased diameter between the second terminal end and the midpoint;

increased diameter and each of the first region of decreased diameter and the second region of decreased diameter; and

5 wherein the clutch includes a spiral cut in at least a portion of the outside diameter of the clutch.

10 2. The dart plunger of claim 1 wherein the spiral cut in the outside diameter of the clutch begins on a top surface of the clutch and ends on a bottom surface of the clutch.

15 3. The dart plunger of claim 2 wherein the inside diameter of the clutch further includes an undulating inside diameter so that the entire inside diameter of the clutch does not create the frictional interface with the dart.

4. The dart plunger of claim 3 wherein the first position of the dart is an open position such that fluids from a well can flow through the dart plunger.

15 5. The dart plunger of claim 3 wherein the second position of the dart is a closed position such that fluids from a well do not flow through the dart plunger.

20 6. The dart plunger of claim 1 wherein the spiral cut extends from the outside diameter to the inside diameter of the clutch.

25 7. The dart plunger of claim 6 wherein the clutch further includes a bore having a spiral cut surface in contact with the dart's shaft as the dart moves between the first and second position.

8. The dart plunger of claim 7 wherein the spiral cut surface in the clutch's bore extends from a top surface to a bottom surface of the clutch.

30 9. The dart plunger of claim 8 wherein the spiral cut surface in the clutch's bore extends continuously from the top surface to the bottom surface of the clutch.

35 10. The dart plunger of claim 9 wherein the clutch may be positioned on the shaft's first region of decreased diameter, the shaft's second region of decreased diameter, or the shaft's region of increased diameter.

11. The dart plunger of claim 10 wherein the clutch is oriented in the dart plunger to repeatedly transition between being positioned on either of the shaft's first region of decreased diameter, the shaft's second region of decreased diameter, and the shaft's region of increased diameter.

12. The dart plunger of claim 5 wherein the clutch may be positioned on the shaft's first region of decreased diameter, the shaft's second region of decreased diameter, or the shaft's region of increased diameter.

13. The dart plunger of claim 12 wherein the clutch is oriented in the dart plunger to repeatedly transition between being positioned on either of the shaft's first region of decreased diameter, the shaft's second region of decreased diameter, and the shaft's region of increased diameter.

14. The dart plunger of claim 1 including an end nut, wherein the clutch seats in the end nut.

15. The dart plunger of claim 14 wherein the end nut includes sidewalls.

16. The dart plunger of claim 15 wherein the sidewalls include a cutout.

17. The dart plunger of claim 16 wherein the cutout is sized to receive the clutch therethrough.

18. A dart plunger, comprising:
a dart having a first position in the dart plunger and a second position in the dart plunger, wherein the dart is configured in the dart plunger to move between the first and the second position;
the dart including a shaft having a first terminal end, a second terminal end, a midpoint equidistant between the first terminal end and the second terminal end, a region of increased diameter at the midpoint, a first region of decreased diameter between the first terminal end and the midpoint, and a second region of decreased diameter between the second terminal end and the midpoint;

end and the midpoint, and a second region of decreased diameter between the second terminal end and the midpoint, whereby the first region of decreased diameter has a first length, the second region of decreased diameter has a second length, and the first length and the second length are substantially equal;
a clutch for retarding movement of the dart between the first and the second position via a frictional interface with the shaft's region of increased diameter and each of the first region of decreased diameter and the second region of decreased diameter.

19. The dart plunger of claim 18 wherein the clutch is a one-piece unit having a length, an outside diameter, and an inside diameter where the inside diameter is sized to create the frictional interface with the shaft's region of increased diameter and each of the first region of decreased diameter and the second region of decreased diameter.

20. The dart plunger of claim 19 wherein the clutch includes a spiral cut in at least a portion of the outside diameter of the clutch.

21. The dart plunger of claim 20 wherein the spiral cut in at least the portion of the outside diameter of the clutch begins on a top surface of the clutch and ends on a bottom surface of the clutch.

22. The dart plunger of claim 21 wherein the inside diameter of the clutch further includes an undulating inside diameter so that the entire inside diameter of the clutch does not create the frictional interface with the dart.

23. The dart plunger of claim 22 wherein the first position of the dart is an open position such that fluids from a well can flow through the dart plunger.

24. The dart plunger of claim 23 wherein the second position of the dart is a closed position such that fluids from the well do not flow through the dart plunger.

25. The dart plunger of claim 24 wherein the frictional interface between the clutch and the dart's shaft imparts more friction on the dart's shaft in the region of increased diameter than either of the first region of decreased diameter or the second region of decreased diameter.

26. The dart plunger of claim 20 wherein the spiral cut extends from the outside diameter to the inside diameter of the clutch.

27. The dart plunger of claim 26 wherein the clutch further includes a bore having a spiral cut surface in contact with the dart's shaft as the dart moves between the first and second position.

28. The dart plunger of claim 27 wherein the spiral cut surface in the clutch's bore extends from a top surface to a bottom surface of the clutch.

29. The dart plunger of claim 28 wherein the spiral cut surface in the clutch's bore extends continuously from the top surface to the bottom surface of the clutch.

30. The dart plunger of claim 29 wherein the clutch may be positioned on the shaft's first region of decreased diameter, the shaft's second region of decreased diameter, or the shaft's region of increased diameter.

31. The dart plunger of claim 30 wherein the clutch is oriented in the dart plunger to repeatedly transition between being positioned on either of the shaft's first region of decreased diameter, the shaft's second region of decreased diameter, and the shaft's region of increased diameter.

32. The dart plunger of claim 24 wherein the clutch may be positioned on the shaft's first region of decreased diameter, the shaft's second region of decreased diameter, or the shaft's region of increased diameter.

33. The dart plunger of claim 32 wherein the clutch is oriented in the dart plunger to repeatedly transition between being positioned on either of the shaft's first region of decreased diameter, the shaft's second region of decreased diameter, and the shaft's region of increased diameter.

34. The dart plunger of claim 18 including an end nut, wherein the clutch seats in the end nut.

35. The dart plunger of claim 34 wherein the end nut includes sidewalls.

36. The dart plunger of claim 35 wherein the sidewalls include a cutout.

37. The dart plunger of claim 36 wherein the cutout is sized to receive the clutch therethrough.

38. The dart plunger of claim 18 wherein the region of increased diameter has a third length, whereby the third length is substantially equal to the first length and the second length.

39. A dart plunger, comprising:
a dart having a first position in the dart plunger and a second position in the dart plunger, wherein the dart is configured in the dart plunger to move between the first and the second position;

the dart including a shaft having a first terminal end, a second terminal end, a midpoint equidistant between the first terminal end and the second terminal end, a region of increased diameter at the midpoint, a first region of decreased diameter between the first terminal end and the midpoint, and a second region of decreased diameter between the second terminal end and the midpoint;

a clutch for retarding movement of the dart between the first and the second position, wherein the clutch is a one-piece unit having a length, an outside diameter, and an inside diameter, wherein the inside diameter is sized to create a frictional interface with the shaft's region of increased diameter and each of the first region of decreased diameter and the second region of decreased diameter,

wherein the clutch includes a spiral cut in at least a portion of the outside diameter of the clutch, and the spiral cut extends from the outside diameter to the inside diameter, and

wherein the clutch further includes a bore having a spiral cut surface that extends from a top surface to a bottom surface of the clutch.

40. The dart plunger of claim 39 wherein the spiral cut surface in the clutch's bore extends continuously from the top surface to the bottom surface of the clutch.

41. The dart plunger of claim 40 wherein the clutch may be positioned on the shaft's first region of decreased diameter, the shaft's second region of decreased diameter, or the shaft's region of increased diameter.

42. The dart plunger of claim 41 wherein the clutch is oriented in the dart plunger to repeatedly transition between being positioned on either of the shaft's first region of decreased diameter, the shaft's second region of decreased diameter, and the shaft's region of increased diameter.
